UNITED STATES PATENT OFFICE.

THOMAS E. WOOD, OF BOSTON, MASSACHUSETTS.

IMPROVEMENT IN PHOTOGRAPHIC CAMERAS.

Specification forming part of Letters Patent No. 42,524, dated April 26, 1864.

To all whom it may concern:

Be it known that I, THOMAS E. WOOD, of Boston, in the county of Suffolk and State of Massachusetts, have invented a new and useful machine to be applied to and connected with the instrument known as the "camera obscura," for the purpose of moving in a horizontal and perpendicular direction one or more tubes of said instrument, and to be known as the "independent camera-tube mover;" and I do hereby declare that the following is a full, clear, and exact description of the construction and operation of the same, reference being had to the accompanying drawings by numbers and letters, making them a part of this specification, in which—

Figure 1 is a perspective view showing the door or slide moved horizontally to the left from the center; Fig. 2, a front elevation; Fig. 3, a horizontal section through A B; Fig. 4, a longitudinal section.

Letters A B is a line on which the section shown in No. 3 is made.

C is a circular opening in the door or slide E, for the purpose of inserting the lens or tube.

D D are two perpendicular bars, on which the door or slide E E is moved up and down by means of the thumb-screw and pinion b, which works in the rack f, said rack being inserted and fixed in the perpendicular bar D at the left of the circular opening and behind the door or slide, as shown in horizontal section through A B, No. 3.

F F is a frame back of the door or slide E and fixed to the box H.

G G are two horizontal bars connected with the perpendicular bars D D by the screws d d on the under side of the upper bar and the upper side of the lower bar G.

g is a tongue which slides in the groove h in the horizontal parts of the frame F.

e is a screw and pinion which works in the rack i, said screw being on the back of the upper horizontal bar G.

i, the rack in which the pinion works, is placed on the back of the upper horizontal frame, F, as shown in longitudinal section, No. 4. The action of pinion e, moving in rack i, produces the horizontal movement of the door or slide E E.

The door or slide is constructed of a thin piece of wood, having a circular opening cut in the center and clamped on the sides with two upright pieces of the same material. On the back of the door or slide are cut verti-

cally from top to bottom two dovetailed notches, in which are inserted two vertical bars of dovetail section, said bars being so constructed that the door or slide can be moved on them up and down freely, said bars being fastened by screws or otherwise to two horizontal bars near the top and bottom of said vertical bars, said horizontal bars being so constructed as not to interfere with the vertical movement of the door or slide. On the under side of the upper and the upper side of the lower horizontal bars is a tongue running the whole length of each bar, inserted and sliding in two grooves in a frame back of the door or slide and between the two said longitudinal bars.

The frame is constructed of four pieces of wood, two horizontal and two vertical pieces. The vertical pieces are tenoned into the horizontal pieces at top and bottom. Said frame is attached by screws to a box inclosed on four sides—viz., sides, top, and bottom.

On the left of the circular opening is a thumb screw, connected with which is a pinion which moves in a rack, said rack being let into and fixed to the small vertical bar to the left of the circular opening, by means of which the door or slide is moved up and down on the vertical bars.

In the center of the upper horizontal bar, and back of it, is attached a thumb-screw, placed vertically, connected with which is a pinion which works in a rack, said rack being inserted and fixed upon the horizontal piece of the frame on the back and flush with the top of said frame.

What I claim as my invention, and desire to secure by Letters Patent, is—

The construction of a thin piece of board, square or otherwise, with a circular or other opening for the purpose of admitting the lens or tube, in which said board are cut two vertical dovetailed notches, inserted in which dovetailed notches are two vertical bars, which said vertical bars are fastened at top and bottom to two horizontal bars or pieces tongued and inserted in grooves, so as to work or slide freely, said bars and board being so arranged as to be moved by means of pinions and racks in a continuous vertical or horizontal direction.

THOMAS E. WOOD.
